CLAIM

The ornamental design for a surgical robot arm, as shown and described.

DESCRIPTION

FIG. 1 is a top, right-side, front perspective view of a surgical robot arm;

FIG. 2 is a front elevation view of the surgical robot arm of FIG. 1;

FIG. 3 is a back elevation view of the surgical robot arm of FIG. 1;

FIG. 4 is a left-side elevation view of the surgical robot arm of FIG. 1;

FIG. 5 is a right-side elevation view of the surgical robot arm of FIG. 1;

FIG. 6 is a top plan view of the surgical robot arm of FIG. 1; and,

FIG. 7 is a bottom plan view of the surgical robot arm of FIG. 1.

In the drawings, the broken lines are for the purpose of illustrating environment only and form no part of the claimed design.
